(57) **CLAIM**

The ornamental design for a flange alignment piping tool, as shown and described.

DESCRIPTION

FIG. 1 is a perspective view of a flange alignment piping tool according to the present application.

FIG. 2 is a front view of the flange alignment piping tool of FIG. 1.

FIG. 3 is a rear view of the flange alignment piping tool of FIG. 1.

FIG. 4 is a right view of the flange alignment piping tool of FIG. 1.

FIG. 5 is a left view of the flange alignment piping tool of FIG. 1.

FIG. 6 is a top view of the flange alignment piping tool of FIG. 1; and,

FIG. 7 is a bottom view of the flange alignment piping tool of FIG. 1.

1 Claim, 4 Drawing Sheets

FIG. 2
